US00D600298S

(12) United States Design Patent
Serrano et al.

(10) Patent No.: US D600,298 S
(45) Date of Patent:  Sep. 15, 2009

(54) BADGE FOR A GOLF CLUB HEAD

(75) Inventors: Anthony D. Serrano, Anthem, AZ (US);
Xiaojian Chen, Phoenix, AZ (US)

(73) Assignee: Karsten Manufacturing Corporation,
Phoenix, AZ (US)

() Term: 14 Years

(21) Appl. No.: 29/335,796

(22) Filed: Apr. 22, 2009

(51) LOC (9) Cl. 21-02

(52) U.S. Cl. D21/759

(58) Field of Classification Search D21/733-753,
D21/759; 473/324-331, 340-346, 350, 251-256
See application file for complete search history.

Primary Examiner—Mitchell I Siegel

(57) CLAIM

The ornamental design of a badge for a golf club head, as shown and described.

DESCRIPTION

FIG. 1 is a perspective view of a badge for a golf club head, the broken line showing of the golf club head is for illustrative purposes only and forms no part of the claimed design;

FIG. 2 is an enlarged top perspective view of the badge for a golf club head only;

FIG. 3 is a front view of FIG. 2;

FIG. 4 is a rear view of FIG. 2;

FIG. 5 is a top view of FIG. 2;

FIG. 6 is a bottom view of FIG. 2;

FIG. 7 is a right side view of FIG. 2; and,

FIG. 8 is a left side view of FIG. 2.

The broken line showing of the markings on the badge for a golf club head is for illustrative purposes only and forms no part of the claimed design.
